ATTORNEY

UNITED STATES PATENT OFFICE.

CHARLES H. HADLEY, OF NEW LONDON, CONNECTICUT.

SHEAVE FOR PULLEY-BLOCKS.

SPECIFICATION forming part of Letters Patent No. 223,795, dated January 20, 1880.

Application filed October 15, 1879.

To all whom it may concern:

Be it known that I, CHARLES H. HADLEY, of New London, in the county of New London and State of Connecticut, have invented certain new and useful Improvements in Sheaves for Tackle-Blocks; and I do hereby declare the following to be a full, clear, and exact description of the invention, such as will enable others skilled in the art to which it applies to make and use the same, reference being had to the accompanying drawings, and to letters of reference marked thereon, which form a part of this specification.

This invention relates to sheaves or pulleys for tackle-blocks which are provided with devices for lessening friction and strain; and it consists in the construction and combination hereinafter particularly set forth and claimed.

In the accompanying drawings, Figure 1 represents a side elevation of my improved sheave, one of its side plates having been removed. Fig. 2 represents a side elevation of said sheave, one of its side plates and all of its loose anti-friction devices having been removed; and Figs. 3, 4, and 5 represent, respectively, detail views of said detached side plate, the loose inner ring, and one of the numerous rollers. Fig. 6 is a vertical sectional view of my sheave.

A designates the wooden part of the sheave, which is grooved in its periphery, as usual, and provided with a circular central recess to receive the anti-friction devices hereinafter described. An annular metallic bushing, B, lines the interior of said sheave, surrounding said central recess or opening.

C C' designate two metal side plates, of circular form and less diameter than said sheave, which are set into the sides of the latter, and secured in any convenient manner thereto. These plates have central openings, c c', to allow the passage through them of the shaft or spindle on which the sheave turns. D designates a loose metallic ring or hub, which sets between said plates so that its central opening (though somewhat smaller) makes the transverse passage from opening c to opening c' continuous. This ring is concentric with the aforesaid shaft or spindle, and surrounds the same. E designates a number of anti-friction rollers, which are arranged in the annular space between said ring D and bushing B, so as to fill said space. They turn freely against one another and against said

ring, leaving the latter also free to turn, though holding it in position. When the plates C C' are firmly attached to the sides of the sheave, the said ring D and rollers E are secured in their proper positions, without any need of 60 journals or blocks or any form of fastening or attachment whatsoever.

As the aforesaid devices B, E, and D are all of the same material, they will wear evenly, and bushing B protects the wooden part of 65 the sheave against any wear whatsoever. The sheave will therefore last a very long time.

The loose arrangement of the anti-friction devices D and E causes the sheave to work very easily. The extreme simplicity of form 70 of parts B, D, and E, which are all plain cylinders, and C and C', which are circles, renders their construction by casting very easy, and nothing more remains but the turning of the wooden part of the sheave.

Owing to the absence of any unusual forms and the reduction of the parts of the device to the lowest possible number, I am enabled to manufacture these sheaves very cheaply, and to put them upon the market at a low 80 figure, notwithstanding their obvious excellence.

I am aware that sheaves have heretofore been constructed with a loose bearing-ring surrounded by anti-friction rolls, said rolls 85 and ring being held in place by an angle-iron plate, and I do not claim such construction; but

What I do claim, and desire to secure by Letters Patent, is—

1. The combination of flat disk-plates C C', one on each side of the sheave, with a loose inner ring and an outer series of rolls, substantially as described.

2. In a sheave, the combination of fixed 95 side plates with a rotary bearing-ring and a surrounding series of rotary rolls, said rolls and ring being entirely inclosed between said side plates.

3. In a sheave, the combination of fixed side 100 plates with a rotary bearing-ring, a surrounding series of unjournaled rotary rolls, and a fixed cylindrical outer bearing.

In testimony that I claim the foregoing I have hereunto set my hand this 9th day of 105 October, 1879.

CHAS. H. HADLEY.
